CLAIM

The ornamental design for a cash box, as shown and described.

DESCRIPTION

FIG. 1 is a front, right and top perspective view of a cash box, showing my new design;

FIG. 2 is a rear, left and bottom perspective view of FIG. 1; FIG. 3 is a front, right, and top exploded perspective view of FIG. 1;

FIG. 4 is a front view of FIG. 1;

FIG. 5 is a rear view of FIG. 1;

FIG. 6 is a left side view of FIG. 1;

FIG. 7 is a right side view of FIG. 1;

FIG. 8 is a top plan view of FIG. 1;

FIG. 9 is a bottom plan view of FIG. 1; and,

FIG. 10 is a top, front, left perspective view of FIG. 1 shown in a closed configuration.

The broken lines shown in the drawings illustrate portions of the cash box that form no part of the claimed design.

1 Claim, 10 Drawing Sheets
